UNITED STATES PATENT OFFICE.

FREDERICK MAUSSNER, OF PHILADELPHIA, PENNSYLVANIA.

MACHINE FOR INTERLACING CURLLED HAIR.

1,220,663.

Specification of Letters Patent. Patented Mar. 27, 1917.

Application filed September 28, 1916. Serial No. 122,616.

To all whom it may concern:

Be it known that I, FREDERICK MAUSSNER, a subject of Germany, residing at Philadelphia, in the county of Philadelphia and 5 State of Pennsylvania, have invented certain new and useful Improvements in Machines for Interlacing Curled Hair, of which the following is a specification.

My invention relates to a machine for interlacing curled hair in which the curled hair is passed under a row of reciprocating needles having barbs thereon which draw a few strands of hair through the block of hair and thus interlace the hair so that the 15 block will retain its shape when removed from the machine.

The object of my invention is to provide a machine in which are embodied various novel features of construction and arrangement of the parts which will be hereinafter fully described and claimed.

In the accompanying drawings, Figure 1. is an end view of my improved machine; Fig. 2. is a vertical, longitudinal section on 25 line 2—2 Fig. 1; Fig. 3. is a transverse section on line 3—3 Fig. 2; Fig. 4 is a perspective view of the grate for holding the hair when it is being passed through the machine; and Fig. 5. is a perspective view of 30 the base block over which the grate fits when in position upon the machine, and also showing thereon a molding frame for shaping the loose hair into the form desired.

The machine consists of the frame 1, having 35 upright bearing members 2 and 3, in which is mounted the main shaft 5 rotated by any suitable means. In the upper portion of the bearing members 2 and 3 are slidably mounted the reciprocating members 6 and 7 carrying the needle bar 8, to which are secured the needles 9. The reciprocating members 6 and 7 are each provided with heads 10, which are adjustably mounted upon the guides 12, on the reciprocating 45 members.

Each of the heads 10 is adjustably secured upon the reciprocating member by a threaded rod 14 engaged by a wheel 15 having a threaded aperture formed therein to 50 receive said rod. Said wheel 15 is rotatably held in the reciprocating member and it is provided with teeth which mesh with a gear wheel 16 on the shaft 17 carrying a hand

wheel 18. The adjustable heads 10 are each provided with a stud shaft 20 to receive 55 one end of a connecting rod 21 having the other end thereof connected with a stud shaft 23 on the disk 24 secured upon the main shaft 5.

When the main shaft 5 is rotated the reciprocating members 6 and 7 will be moved 60 up and down in the bearing members 2 and 3. By rotating the hand wheels 18 at either side of the machine the position of the adjustable heads 10 may be changed and the 65 position of the needle bar in relation to the main shaft may be thus changed.

The frame 1, of the machine supports longitudinal tracks 27 and 28 on which is mounted the carriage 30, having wheels 31, 70 which run upon the said tracks. The carriage 30 consists of the top and the depending sides 33 and 34 which latter are provided with teeth 35 forming racks engaged by toothed wheels 37 and 38, secured on the 75 counter shaft 40, mounted in the frame of the machine. Upon the counter shaft 40 is secured a ratchet wheel 41 engaged by a pawl 42 on an arm 43 loosely mounted on the counter shaft 40. The arm 43 is oscillated by a cam 45 upon the main shaft 5, which will move the carriage 30 in the direction of the arrow Fig. 2.

The counter shaft 40 is provided with a handle 47 for rotating the said shaft in the 85 opposite direction to return the carriage to the position shown in Fig. 2. This may be done by lifting the pawl 42 free from the ratchet wheel 41. The carriage 30 is made sufficiently long so that the rack 35 will always be in mesh with the gear wheels 37 and 38, when the carriage 30 is at the extreme ends of the machine.

The base block 50 rests upon the carriage 30, which latter is provided with longitudinal ribs 48 which fit into grooves 51 formed in the under side of the base block 50 and insure the base block always being in proper alignment with the machine.

The grate 60 consists of two side plates 100 61 and 62 and a number of U-shaped bars 63 bolted together by bolts 65 and 66 which are located at the extreme lowest portions of the vertical end portions of the U-shaped bars 63 for the purpose of allowing the 105 needles to pass over them without striking

the bolts and breaking the needles. The bars 63 are separated by filling blocks or washers 67 and the entire grate is tightly bolted together by the nuts 68 upon the ends of the 5 bolts 65 and 66. Said bolts 65 and 66 project beyond the side plates 61 and 62 to form places for attaching hoisting mechanism for lifting the grate.

The base block 50 has a raised surface 53 10 around which the grate 60 fits and the latter may be pressed downwardly by means of the rollers 70 and 71 to compress the hair which is placed upon the surface 53 of the base block before the grate is placed over the 15 same. The rolls 70 and 71 are provided with corrugations which hold the upper edges of the grate bars 63 in alinement so that they will pass between the needles.

It will be seen that by having the grate 20 bars 63 entirely separated from each other above the surface 53 of the base block 50 and by having the connecting bolts 65 and 66 located below the surface 53 of the base block, that the machine can be started without first 25 adjusting the grate so that the needles are inside of the ends of the grate. With this construction of the grate the machine may be started with the grate in the position shown in Fig. 2, and the grate advanced into 30 the path of the needles without the needles striking any part of the grate and the latter may continue to move beyond the needles without the machine being first stopped.

When the carriage 30 is being returned to 35 the starting position, shown in Fig. 2, it is desirable to move the needles 9 far enough away from the hair in the grate so that the barbs upon the needles will not hold the hair upon the needles. To quickly raise the 40 needles from the operating position the needle bar is pivotally mounted in the reciprocating members 6 and 7, as shown in Figs. 1 and 2. The needle bar 8 may be loosely mounted upon a shaft 13 or the ends 45 of the shaft may be free to turn in the reciprocating members 6 and 7.

A handle 75 is provided at either end of the needle bar 8 for swinging the latter into the position shown in dotted lines, Fig. 2. 50 Brackets 76 are secured upon the reciprocating members 6 and 7 and said brackets are provided with spring catches 77 for holding the handle in either a vertical or an oblique position.

To facilitate in producing a block of hair which when it is finished it will have a particular size and shape and also contain the proper weight of hair, a molding frame 80 is provided, as shown in Fig. 5. The molding 55 frame 80 consists of the vertical walls and is open at the top and bottom. The molding frame may be any size and shape desired for producing cushions, pads, mattresses and the like. The molding frame is placed upon 60 the base block 50 and filled with the re-

quired weight of hair to form the finished article.

The molding frame 80 is then removed from the base block, leaving the block of hair upon the base block; the rack 60 is then 70 lowered over the base block to hold the hair while being interlaced by the needles.

Having thus described my invention I claim and desire to secure by Letters Patent:—

75

1. In a machine of the character described, the combination of a frame having side members, reciprocating members slidably mounted in the side members of the frame, and a needle bar pivotally mounted 80 in the said reciprocating members.

2. In a machine of the character described, the combination of a frame having side bearing members, reciprocating members slidably mounted in the side bearing members, a shaft extending between the reciprocating members, and a needle bar rotatably supported by said shaft. 85

3. In a machine of the character described, the combination of a frame having side bearing members, reciprocating members slidably mounted in the side bearing members, a needle bar pivotally mounted in the reciprocating members, and means for locking the needle bar in a fixed position in relation 90 to the reciprocating members.

4. In a machine of the character described the combination of a frame, reciprocating members mounted in the frame, a needle bar pivotally mounted in the reciprocating members, a handle upon the needle bar for rotating the latter, a bracket mounted in a fixed position for engaging the needle bar and locking the same in relation 100 to the reciprocating members. 105

5. In a machine of the character described the combination of a frame, reciprocating needles mounted in said frame, a carriage, a base block, a grate adapted to fit over the base block and hold material upon 110 the base block, and said grate having bars secured together at points below the plane of the top surface of the base block.

6. In a machine of the character described the combination of a frame, reciprocating 115 needles mounted in said frame, a grate mounted in the frame holding material to be treated by the needles, U-shaped bars forming said grate, and bolts securing the said grate bars together at points below the 120 lowest point in the stroke of the reciprocating needles.

7. In a machine of the character described the combination of a frame, reciprocating needles mounted in said frame, a grate adapted to hold material to be treated by the needles, inverted U-shaped bars forming the said grate, bolts holding the ends of the 125 grate bars together, filling pieces on said bolts to separate the grate bars and side 130

plates forming the side walls of the grate.

8. In a machine of the character described
the combination of a frame, reciprocating
needles mounted in the frame, a carriage,
5 base block on said carriage, a removable
molding frame for holding the material to
be treated by the needles, and a grate adapt-
ed to be placed over the molded hair on the

base block after the molding frame has
been removed.

10

In testimony whereof I affix my signature
in the presence of two witnesses.

FREDERICK MAUSSNER.
